UNITED STATES PATENT OFFICE.

WILBER A. K. CAMPBELL, OF ELDORA, IOWA.

DEVICE FOR APPLYING ADHESIVES TO EDGES OF WRAPPERS.

SPECIFICATION forming part of Letters Patent No. 540,717, dated June 11, 1895.

Application filed September 14, 1894. Serial No. 523,008. (No model.)

To all whom it may concern:

Be it known that I, WILBER A. K. CAMPBELL, a citizen of the United States, residing at Eldora, in the county of Hardin and State of Iowa, have invented certain new and useful Improvements in Devices for Applying Adhesive to the Edges of Wrappers; and I do declare the following to be a full, clear, and exact description of the invention, such as will enable others skilled in the art to which it appertains to make and use the same.

My invention has relation to devices for applying paste or other adhesive to the edges of wrappers for wrapping newspapers for the mails, and among the objects in view is to provide a simple, inexpensive and efficient device for applying adhesive to the edges of newspapers or other wrappers whereby a considerable saving in time and expense is effected, and with the above and other objects in view my invention consists in the novel construction, arrangement and combination of parts as hereinafter fully described, illustrated in the accompanying drawings and pointed out in the appended claims.

In the drawings, Figure 1 is a perspective view illustrating my device in use. Fig. 2 is a vertical longitudinal section thereof. Fig. 3 is a perspective view of the paste fountain or receptacle. Fig. 4 is a rear view of the device.

In carrying out my invention, I provide a base or board 1 upon which the sheets or wrappers to be pasted are laid and which board toward one end is provided upon opposite sides with vertical standards 2, which upon their inner faces are grooved as at 3. The board 1 is preferably made somewhat wider than the wrappers and is provided with a pin 4 which is adapted to perforate the wrappers and hold them securely in position on the board. 5 indicates the paste receptacle or fountain which may be of any suitable construction adapted to hold the paste and the brush by which the paste is applied to the wrappers. I, however, preferably construct the receptacle of a triangular form and open at top as shown. Slidably mounted within wire guides 5' carried by said receptacle is a suitable brush 6, which is adapted to slide vertically. The receptacle is provided with ribs

6' adapted to slide within the grooves 3 of the standards.

In order to hold the brush down against the wrappers at all times, and thus accommodate 55 itself to the diminishing quantity of wrappers, any suitable means may be employed, as for instance a set-screw 7 working within a metallic plate 8 secured to the standards 2, said set screw being adapted to bear against 60 the brush head so as to regulate the brush in its vertical movements; or I may provide the receptacle with openings 13 through which I can insert a pin 14 into previously provided 65 sockets in the brush-head. A suitable opening 10 is formed in the rear side of the receptacle in rear of the brush and adapted to be closed or partially so by a slide 11 to govern the flow of paste on to the wrappers.

In order that the paste receptacle may not 70 retain or scrape off any paste from the wrappers as they are pasted, I provide said receptacle upon each side and at any suitable point in rear of the brush with buttons or protuberances 12 which rest upon the topmost wrapper 75 whereby the bottom edge of the receptacle will be lifted clear of the paste. This is a very desirable feature of my invention.

The operation of my invention may be briefly described as follows:—The wrapper to 80 be pasted having been placed upon the board 1, and over the pin, the set-screw 7 is then adjusted so as to cause the brush to bear on the wrappers. The slide 11 is raised to allow the paste to flow on to the topmost wrapper. The 85 newspaper to be wrapped is then placed in a folded condition upon the wrapper and the latter rolled around the paper at the same time being drawn forward and torn from the pin, and the brush then evenly spreads the 90 paste upon the end of the wrapper which end is finally pasted down and another newspaper may then be wrapped in the next succeeding wrapper. Thus the paste receptacle by sliding vertically downward, automatically 95 accommodates itself to the successively decreasing supply of wrappers, while the brush may also be regulated to suit the decreased number of wrappers.

Having thus described my invention, what 100 I claim, and desire to secure by Letters Patent, is—

1. The combination with a base board, and standards carried thereby, of a paste receptacle vertically adjustable in said standards, and having an outlet for the paste, a slide 5 governing the flow of paste through said outlet and a brush vertically adjustable within said receptacle, and means for adjusting said brush, as described for the purpose specified.
2. The combination with a base board and 10 standards carried thereby, of a paste receptacle vertically adjustable in said standards and provided with an outlet for the paste, a brush carried by the receptacle, and projections on the receptacle adapted to rest on the 15 wrappers to lift the receptacle above the same, for the purpose specified.
3. The combination with a base board and standards carried thereby, of a paste receptacle vertically adjustable in said standards and provided with an outlet for the paste, 20 projections on the receptacle adapted to rest on the wrappers to lift the receptacle above the same, a brush carried by the receptacle and a plate and set-screw adapted to regulate the brush in its vertical movements, substantially as set forth.

In testimony whereof I affix my signature in presence of two witnesses.

WILBER A. K. CAMPBELL.
